CLAIM

The ornamental design for the spherical dynamic resistance tool, as shown and described.

DESCRIPTION

FIG. 1 is a perspective view of the spherical dynamic resistance tool;

FIG. 2 is a side view thereof;

FIG. 3 is a view of other side thereof;

FIG. 4 is a front view thereof;

FIG. 5 is a back view thereof;

FIG. 6 is a top view thereof; and,

FIG. 7 is a bottom view thereof.

The broken lines shown in the drawings depict portions of the spherical dynamic resistance tool that form no part of the claimed design.
